(57) **CLAIM**

The ornamental design for a gas regulator, as shown and described.

DESCRIPTION

FIG. 1 is a front perspective view of a gas regulator showing our new design;

FIG. 2 is a rear perspective thereof;

FIG. 3 is a right side view thereof;

FIG. 4 is a rear view thereof;

FIG. 5 is a front view thereof; and,

FIG. 6 is a top view thereof.

The broken lines shown in the figures are included for the purpose of illustrating portions of the gas regulator and form no part of the claimed design.
